(57) **CLAIM**

We claim the ornamental design for a light fixture, as shown and described.

DESCRIPTION

FIG. 1 is a perspective view of a first embodiment of a light fixture showing our new design.

FIG. 2 is an end view of the light fixture shown in FIG. 1. FIG. 3 is a side view of the light fixture shown in FIG. 1. FIG. 4 is a section view of the light fixture shown in FIG. 1 viewed along section 4-4.

FIG. 5 is a bottom plan view of the light fixture shown in FIG. 1.

FIG. 6 is a perspective view of a second embodiment of a light fixture showing our new design.

FIG. 7 is an end view of the light fixture shown in FIG. 6. FIG. 8 is a side view of the light fixture shown in FIG. 6. FIG. 9 is a section view of the light fixture shown in FIG. 6 viewed along section 9-9.

FIG. 10 is a bottom plan view of the light fixture shown in FIG. 6.

FIG. 11 is a perspective view of a third embodiment of a light fixture showing our new design.

FIG. 12 is an end view of the light fixture shown in FIG. 11. FIG. 13 is a side view of the light fixture shown in FIG. 11. FIG. 14 is a section view of the light fixture shown in FIG. 11 viewed along section 19-19; and,

FIG. 15 is a bottom plan view of the light fixture shown in FIG. 11.

The top views are not part of the claimed design. The portions of the light fixture shown in broken lines form no part of the claimed design. The break lines in the drawings indicate that the appearance of any portion of the light fixture between the break lines forms no part of the claimed design.
